BUTTON STITCHING MACHINE

Mathias Pedersen, Valley Stream, and Robert J. Cook, Westbury, N.Y., assignors to American Machine & Foundry Company, a corporation of New Jersey

Filed Oct. 28, 1964, Ser. No. 407,137
15 Claims. (Cl. 112—113)

This invention relates to stitching machines, and more particularly to machines for stitching or sewing buttons or like fastening devices of a wide range of sizes to articles such as men's and women's coats and other articles of clothing and to other selected types of goods.

The invention relates to button stitching machines preferably of the type disclosed in Patterson et al. Patent 2,739,550; Johnson et al. Patent 3,123,613, granted May 12, 1964; Johnson et al. Patent 3,121,411, granted Feb. 18, 1964; Pedersen Patent 3,125,046, issued Mar. 17, 1964, for Work Support Table for Button Stitching Machine, and copending Johnson application Ser. No. 296,039, filed July 18, 1963, now Patent 3,236,200, for Button Stitching Machine.

In the garment trade different sizes of buttons are used with different types of garments. For example, in the case of sack coats one selected size of button is stitched to the coat front. Generally a larger sized button is attached to the coat front of an overcoat or a topcoat.

Heretofore in the art because of the variations in thickness of materials to which buttons are attached and also the requirements as to size of buttons to be used with different materials, it has not been possible to use a single stitching machine for attaching buttons of a wide range of sizes of different diameters. The present invention solves this problem because it embodies mechanism which makes it possible to use buttons ranging in size from say 25 ligne to say 45 ligne by making adaptations in the machine which can be readily and easily effected in a minimum of time. Thus, a machine embodying the present invention is extremely flexible and versatile because it can be used to attach buttons of any selected size within the wide generally used range of button sizes stitched to thin materials, and to thick materials. In the case of thick materials, such as overcoats and topcoats, usually a button ranging in size between 40 and 45 ligne is used, except in the case of thin raincoats where buttons of the same size range are stitched to the raincoat.

It is an object of the invention to provide a novel button stitching machine having means for feeding and supporting buttons of a widely varying range in diameter in accordance with the type of button selected and the kind of work to which the selected buttons are to be attached.

The invention further comprises the provision of a button stitching machine having novel button storing, feeding and supporting devices which make it possible for the machine to stitch buttons of a wide selection of diameter sizes to materials, such as men's and women's coats, vests and other articles of clothing.

With these and other objects not specifically mentioned in view, the invention consists in certain combinations and constructions which will be fully described hereinafter, and then set forth specifically in the claims hereunto appended.

In the accompanying drawings which form a part of this specification and in which like characters of reference indicate the same or like elements:

FIGURE 1 is a partial plan view showing a preferred form of the invention;

2

FIGURE 2 is a side elevation, partially in section of a button storing and feeding mechanism embodying the invention;

5 FIGURE 3 is a perspective view of button transfer device and button chuck;

FIGURE 4 is a perspective view of a modified form of button transfer and modified form of button chuck;

FIGURE 5 is a side elevation of a button chamber;

10 FIGURE 6 is a perspective view of a button chuck embodying the invention;

FIGURE 7 is a plan view of a modified form of the invention;

15 FIGURE 8 is a view taken on line 8—8 in FIGURE 7 and

FIGURE 9 is a view taken on line 9—9 in FIGURE 7.

Referring to FIGURES 1-6 of the drawings which illustrate a preferred form of the invention, it will be seen that there is provided a button storage designated generally 10, a button feed chute 12, a button receiving and delivery chamber 14, a button transfer 16 and a button holding chuck 18 into which buttons B are delivered by transfer 16. Button chuck 18 is mounted on work supporting table T which is moved in the directions of arrows A and C in timed relationship with the movement of the 20 needle bars (not shown) which pass a threaded double pointed needle (not shown) back and forth from one bar to the other during the formation of loops of thread attaching a button to the work or material, and the formation of wrapping about the loops of thread, and locking 25 stitches which complete each button stitching operation. These operations take place in timed relationship with the other instrumentalities of the machine (not shown) in order that the desired stitching operations incident to the 30 attachment of each button to a selected material can be effected.

35 The construction and operation of the needle bars, (not shown), work table T, work holding means, operating means for button chuck 18, button transfer 16, button chamber 14, thread pullers (not shown) and other operating mechanisms, such as specific drives are essentially the same as disclosed in the patents above referred to. Since these mechanisms do not form a specific part of the 40 present invention, the disclosure herein has been limited to that which is considered necessary to a full understanding of the invention.

45 Referring to FIGURES 1 and 2, button storage 10 comprises an inclined generally V-shaped button rack 20 attached by screws 22 to the machine frame F. The space between walls 24 is designed to allow rack 20 to accommodate the largest diameter size of button which normally is required. For example, rack 20 can hold 45 ligne buttons. A ligne is equal to .025 inch. Therefore, rack 20 can hold buttons 1 1/8" in diameter.

50 An adapter 26 is provided for adapting rack 20 to hold smaller diameter buttons. It is also generally V-shaped in cross section (see FIGURE 1). Two longitudinally spaced aligned pins 28, 29 are carried on the underside of adapter 26. Each pin is provided with two spaced annular grooves 30, 32. The grooves of pin 28 may be seated in a closed keyhole 36; those in pin 29 seat in open keyhole 34. Both keyholes 34 and 36 are formed in the flat 55 central elongated web portion 25 of rack 20. Adapter 26 is mounted in rack 20 by extending pin 28 downwardly through the wide opening part of keyhole 36 and pin 29 downwardly into the open part of keyhole 34 until a selected inner and outer pair of grooves 30 or 32 is positioned therein. Adapter 26 is then pushed longitudinally

relative to rack 20 such that grooves 30 or 32, as the case may be, slide between the spaced walls of the narrow portions of keyholes 34, 36 until they engage the bottom faces thereof, whereby adapter 26 is seated in rack 20 for supporting a smaller size of button. When grooves 30 in pins 28 and 29 engage keyholes 36 and 34, respectively, a range of buttons from, say 28 to 34 ligne, can be stored and fed therefrom for attachment to a selected material. When grooves 32 engage in keyholes 36 and 34 a range of button sizes between say 20 and 26 ligne can be stored. It will be apparent from a consideration of FIGURES 1 and 2, that rack 20 alone, and also with adapter 26 can store a supply of buttons sufficient for attachment to several selected garments. The actual quantity depends upon the length of rack 20 and adapter 26.

In practice buttons are stacked in rack 10, face down. A member 38 having a guard 40 located in front of rack 20 limits the ejection of buttons therefrom to one at a time. Member 38 is pivotally supported in block 42 suitably attached to delivery plate 44 over which a button B slides downwardly into button chute 12 when ejected by ejector 46 from the bottom of rack 20. An adjusting screw 35 threadably supported in block 42 is provided with a conical cam point 37 located beneath member 38. When screw 35 is turned one way or the other, member 38 is raised or lowered by cam point 37 and guard 40 is thereby disposed in proper adjusted position determined by the run of buttons to be attached to the work. Screw 35 is provided with a polygonal collar 39, hexagonal in the form shown, formed integrally therewith or suitably attached thereto. A flat spring 41 mounted on block 42 presses against one face of collar 39 and prevents screw 35 from turning from its selected adjusted position.

The button chute and means for ejecting a button from rack 20 are generally the same as disclosed in Johnson et al. Patent 3,121,411. Therefore, only such showing as is required for a complete understanding of the invention and its relation thereto is illustrated and described herein.

Button ejector 46 is carried on the free end of arm 48 fixed to shaft 50 rotatably supported in suitable bearings formed in bracket 52 mounted on frame F of the machine. A cam lever 54 secured to the lower end of shaft 50 carries cam follower 56 which engages wedge-shaped cam piece 58 carried by horizontal bar 60. Bar 60 is moved forwardly in the manner shown and described in Johnson et al. Patent 3,121,411 in proper timed sequence during the operation of the machine to engage and disengage cam piece 58 with cam follower 56 and cause ejector 46 to eject a button B from rack 10. A spring (not shown) returns bar 60 to its inoperative position after each button ejection. The plane of the lower edge of rack 20 is disposed slightly above the plane of the top surface of ejector 46. The plane of the lower edge of guard 40 is also disposed slightly above the plane of the top surface of ejector 46. The plane of the lower edge of guard 40 clears the top surface of the lowermost button in rack 20 in order to engage the button just above the lowermost button. FIGS. 1 and 2 show the position of ejector 46 just after the lowermost button has been ejected and just before ejector 46 moves away from guard 40 to allow the next button to fall in front of ejector 46.

Button chute 12 in the form shown herein comprises an elongated open generally U-shaped trough 62 into which buttons slide from delivery plate 44, and gravitate into button well 64 in button chamber 14 located at the lower end of chute 12 where it is held by gate 84 until it is delivered to button transfer 16 for delivery to chuck 18.

Buttons are made in many sizes. Commonly used sizes range between 20 ligne to and including 45 ligne. In the trade there are three basic ranges in size. These are 20-26 ligne, 28-34 ligne and 36-45 ligne.

Heretofore, machines available for stitching buttons have been what can be termed a one purpose button stitching machine because the size of buttons it could handle

was limited. In accordance with the invention, provisions are made which make it possible to adapt and convert a button stitching machine capable of attaching a two hole or four hole button of any size over a wide range of button sizes with a minimum of effort and expenditure of time.

It has been found that buttons most used are 24, 30, 40 and 45 ligne. In accordance with one embodiment of the invention, four readily interchangeable button chambers for handling these sizes of buttons are provided. As shown in FIGURE 5, chamber 14 is designed to handle say a 24 ligne button. If a larger size is to be handled, the 24 ligne chamber is removed and rapidly replaced by a chamber capable of handling the selected button size.

15 The mechanism which is disclosed herein for adapting the button stitching machine of which it forms a part to handle a wide range of button sizes coacts with mechanisms disclosed in our copending applications Ser. No. 407,083 and Ser. No. 407,138, both filed on Oct. 28, 20 1964, for Button Stitching Machines, respectively. All of which mechanisms contribute to provision of a button stitching machine having great versatility and flexibility heretofore unknown in the art.

Although four chambers 14 are suggested as satisfying most practical requirements, as many can be provided as are required within practical limits of the machine.

Button chambers 14 are identical in construction and only one is described in detail. Referring to FIGURES 1 and 5, chamber 14 is provided with a mounting extension 30 76 having an elongated recess 78 formed in one face thereof. The height and depth of recess 78 is such that arm portion 68 of lever 70 seats snugly therein when a selected chamber 14 is installed in the machine. The selected chamber 14 (FIGURE 5) comprises a body 71 and is held in operative position on lever 70 by means of screw 80 threadably secured in aligned threaded holes in arm portion 68 and extension 76 of body 71. Each of the several chambers referred to above which are interchangeably mounted in the machine is provided with a 35 similar threaded hole in its extension 76 and after extension 76 is seated against shoulder 79 of lever 70, screw 80 is tightened to secure it in operative position. This construction makes it possible to effect the rapid removal of one chamber 14 and its replacement with another with a minimum of effort and expenditure of time.

40 A button B dropping out of chute 62 into well 64 comes to rest against a shoulder 82 which prevents any further longitudinal movement therein. Button B is held in position between the rear wall of chamber 14 and a movably mounted gate 84, awaiting transfer from chamber 14. In the illustrated embodiment gate 84 is a curved member forming an integral part of an elongated rod 86 rotatably supported in suitable bearings in lugs 88 forming an integral part of bracket 90 attached to chamber 14 by 45 screws 92 (see FIGURE 5). Weight 94 attached to elongated portion 86 of gate 84 normally tends to bias gate 84 out of holding relationship with respect to a button in well 64 as soon as chamber 14 moves from button receiving to position for delivery of a button to transfer 16.

60 Chamber 14 is moved from receiving position where it receives a button from chute 62 clockwise, as viewed in FIGURE 1, to a position where it delivers the button to transfer 16. This movement is effected by means of a lever 96 attached to shaft 72 supporting on its free end 65 a cam follower 98. A spring 100 having one end attached to lever 70 and its other end attached to a pin in the frame of the machine maintains cam follower 98 in engagement with cam 102 mounted on bar 60. It will be evident that when bar 60 moves rearwardly (upwardly, 70 as viewed in FIGURE 1), cam follower 98 which engages the high portion of cam 102 when chamber 14 is in the position shown in FIGURE 1, will travel downwardly onto the low portion of cam 102, whereupon spring 100 will effect the movement of chamber 14 to its 75 button transfer position.

Upon movement of bar 60 in the opposite direction and the engagement of cam follower 98 with the high portion of cam 102, chamber 14 is returned to the position shown in FIGURE 1. At this time a resilient presser finger 104 suitably attached to the frame of the machine is engaged by weight 94 which is moved thereby towards chamber 14. This movement of weight 94 causes gate 84 to be swung up into operative position with respect to well 64 where it coacts with the rear wall of well 64 to support the next button entering well 64 properly for delivery to transfer 16.

A gate finger 106 pivotally mounted on shaft 103 supported in bracket 110 prevents button jams, and insures that only one button at a time can roll into well 64. The free end of finger 106 extends transversely through a notch 112 in chamber 14. Spring 114 having one end attached to finger 106 and its other end fixed to bracket 116 carried by the machine frame normally maintains finger 106 in its operative position in notch 112. In the same manner as described and shown in Johnson et al. Patent 3,121,411, finger 106 is raised and lowered to control the movement of buttons into well 64.

The mechanism for effecting the delivery of a button from a chamber 14 to button transfer 16 is generally the same as that shown and described in Johnson et al. Patent 3,121,411. Therefore, the description and disclosure herein is limited to only as much as is necessary to a full understanding of the invention. As in the machine described and shown in this patent, depression of treadle 120 which is connected by suitable linkage to lever 122 attached to shaft 124 causes the latter to rock in such manner that bar 60 moves rearwardly or upwardly as viewed in FIGURE 1. This action disengages the high portion of cam 102 from cam follower 98 and allows spring 100 to swing chamber 14 into button delivery position with respect to transfer 16.

After the first of a series of buttons to be attached to the work has been delivered to transfer 16, subsequent buttons are delivered automatically. This operation is effected in the same manner as that disclosed and described in Johnson et al. Patent 3,121,411 by means of cam 126 fixed to shaft 128 which makes one complete revolution during each stitching operation of the machine. Cam 126 is tracked by cam follower 130 carried by lever 132 from which extends an adjustable stud 134 operative to engage block 136 fixed to lever 138 in the same manner as described in the above referred to patent. Substantially concurrently with the movement of chamber 14 to button delivery position relative to transfer 16 the button supporting and injecting head 153 of transfer 16 is rotated in order to allow hooked button supporting pins 148 to become aligned with the holes of the button to be transferred such that as chamber 14 moves forwardly a button carried thereby can be pushed onto hooked button supporting pins 148 where the button remains as chamber 14 moves back to its button receiving position shown in FIGURE 1.

Button transfer 16 includes a gear segment 150 meshing with gear 152 on button injecting head 153 which supports button carrier pins 148. Segment 150 is oscillated in order to align pins 148 with the holes of a button when each button is to be delivered by chamber 14 onto pins 148. This oscillation is effected manually by treadle 120, and linkage connected to lever 122 on shaft 124 for the first of a series of stitching cycles to attach a run of buttons to selected garments. Orientation of pins 148 and delivery of buttons therein is also effected automatically by means of a connecting rod 172 pivotally secured at one end to segment 150, and loosely connected at its other end to an L-shaped horizontal member 176 attached to lever 136 on shaft 124.

Referring to FIGURES 3 and 4, it will be seen that button transfer 16 comprises a sleeve in which is reciprocably slidably mounted an elongated plunger (not shown) which supports the button orienting and support-

ing pins 148. Resilient pins 148 are formed with hooks on their free ends in order to receive, support and prevent button from being removed therefrom until it is lodged between the jaws of button chuck 18 described more in detail hereinafter. Bevel gear 152 which meshes with gear segment 150 is fixedly attached to head 153. Gear 152 is provided with a reduced hub 154. In accordance with the invention, means are provided which make it possible to successfully transfer buttons of a wide range of sizes from chamber 14 to button chuck 18. In the novel structure shown in FIGURE 3 button transfer 16 is designed for holding and transferring a button less than 40 ligne in size. Head 153 is provided with an adapter ring 156 secured thereto by a set screw (not shown). The inner diameter of ring 156 engages head 153 and the inner-diameter shoulder 155 of ring 156 engages pins 148 as shown in the cut-away portion of ring 156 in FIG. 3. The outer diameter of ring 156 is of a size such that when a button is seated on pins 148 the rim on the top or exposed side of a button will rest against the exposed edges of ring 156, and not against the face of a button. This is important in proper handling of buttons and buttons for delivery into button chuck 18 inasmuch as the faces of buttons can vary quite considerably, and accuracy in handling cannot otherwise be obtained. In button chuck 18 disclosed in FIGURE 3, jaws 160 and 162 are formed to hold a button of less than 40 ligne size.

Referring now to FIGURE 4, the construction and operation of button transfer 16 is the same as that described hereinabove. The only difference is that a different type of adapter ring 164 is provided in order to adapt the machine for stitching buttons of 40-45 ligne. Adapter ring 164 is secured by a suitable set screw 158 to head 153. It is provided with a beveled outer face 165 and a button rim contacting face 166 having an outer diameter corresponding to the outer diameter of the rim of a button such that the collar can engage the rim only on the face of a button for the same reasons given above. Button chuck 18 is the same as that disclosed in FIGURES 1 and 3 with the exception that the jaws 160a and 162a which have a no-offset type of holding means 161a and 163a, respectively, are designed to hold a button of the 40-45 ligne range.

In the button transfer mechanism disclosed in FIGURES 3 and 4 the design is such that transfer head 153 can support adapter rings suitable for handling all sizes of buttons referred to hereinabove. In general, however, it has been found that two rings which enable the machine to handle 24-30 and 40-45 ligne buttons, respectively, will answer most normal practical requirements.

Referring to FIGURES 1 and 6 it is to be noted that button chuck 18 is supported in a bracket 180 suitably mounted on table T which is moved during the operation of the machine along lateral, longitudinal and diagonal paths of travel in order to allow the machine to perform the necessary stitching operations in the attachment of a button to the work. The mechanism for operating the table forms no specific part of the invention, it can be the same as disclosed in Pedersen Patent 3,125,046 or Patterson et al. Patent 2,739,550. and therefore no further description or disclosure is considered to be necessary to an understanding of its operation.

The construction and operation of button chuck 18 is essentially the same as that disclosed in Johnson et al. Patent 3,121,411 with the exception that novel means are provided for making it possible to handle a complete range of button sizes in the three ranges described hereinabove without the necessity of removing and replacing the entire button chuck in order to effect the desired changeover from one size button to another.

Button chuck 18 comprises two suitably shaped jaws 160, 162 having button means 161, 163, respectively, slidingly supported in a housing or member 200 secured

to a swivel head 202 rotatably mounted in bracket 180. Swivel head 202 is provided with a stud shaft (not shown) to which is secured a gear (not shown) and driving means (not shown) for moving head 202 and chuck jaws 160, 162 from vertical button receiving position, horizontal stitching position and vertical position for completion of stitching operations by the same mechanism as disclosed in Johnson et al. 3,121,411. The means for opening jaws 160 and 162 to receive a button therebetween and to release it after stitching operations have been completed also are the same as described and claimed in said Johnson et al. patent.

In accordance with the invention, housing 200 is provided with a removable face plate 204, normally held in operative assembled position by screws 206 in housing 200. This housing also is formed with two parallel grooves 208, 210 in which slideable extensions 212 and 214 on jaws 160 and 162, respectively, are mounted for sliding movement to and from each other for receiving, holding and releasing buttons.

Actuating lever 216, which corresponds to lever 216, disclosed in Johnson et al. Patent 3,121,411 and operates in the same manner, is provided with two half pins 218, 220 which engage in recesses 222, 224 in extensions 212, 214 of jaws 160 and 162. The depth of the recesses is greater than the maximum interrupted diameter of pins 218, 220 to provide for the desired freedom of movement of jaws 160, 162 without binding. Lever 216 is fulcrumed on pin 226 mounted in a central lug in housing 200. Jaws 160 and 162 are operated by actuating bar 230 similar to bar 230 disclosed in said Johnson et al. Patent 3,121,411, which engages lever 216 when jaws 160, 162 are disposed in button receiving or releasing positions.

Jaws 160 and 162 are modelled so as to cover the entire range of buttons from say 20-45 ligne. In the case of buttons ranging from say 20-39 ligne, jaws 160, 162 are formed with an offset arrangement as shown in FIGURES 3 and 6. In the case of buttons from 40-45 ligne, the construction shown in FIGURE 4 is used. Extensions 212 and 214 on each corresponding jaw are the same in order to provide for their sliding seated operative mounting in housing.

When a selected set of jaws has been mounted in housing 200 shown in FIGURE 6, cover plate 204 is seated on housing 200 with screws 206 extending upwardly through recess 207 and keyhole opening 209. Plate 204 is moved to the left, as viewed in FIGURE 6, to engage one screw 206 in reduced opening portion 211, after which screws 206 are turned home to secure plate 204 in proper assembled relation on housing 200. The adapted chuck 18 is then ready for use in accordance with its selected button size. Any desired interchange of pairs of jaws can readily and rapidly be made in the manner described.

FIGURES 7, 8 and 9 disclose a modified form of button receiving and delivery mechanism embodying the invention. This mechanism is capable of handling the entire range in size of buttons discussed hereinabove. That is, it can receive, hold and deliver to transfer 16 buttons ranging from 20 ligne to 45 ligne. If smaller or large buttons were selected for use it could be designed to handle them also. As shown in FIGURES 7 and 8, this mechanism comprises a chamber designated generally 250, having a body portion 252 and a mounting extension 254 preferably formed integrally therewith. An elongated recess 256 formed in one face of extension 254 has an extension 254 such that it can be mounted on arm portion 68 of lever 70 and secured thereon by screw 80, as in the case of a selected button chamber 14. Chamber 250 is moved clockwise, as viewed in FIGURE 7, by spring 100 from button receiving position to delivery position relative to button transfer 16 as the result of the movement of cam 102 upwardly, as viewed in FIGURE 7, and the displacement of cam follower 98 onto low cam portion 103. This action is the same as that of chamber 14.

Referring to FIGURE 8, a button delivered by chute 62 comes to rest in receiving well 256 formed by the rear wall of body 252, outwardly extending lugs 258 and 260, and arcuate lug 262, all arranged along the periphery of a circle of which the center of opening 263 is the center of the circle. Opening 263, as in the case of opening 83 in a chamber 14 provides space for the projection of pins 148 as they extend through the holes of a button during its pick-up and transfer from a chamber to button transfer 16.

Each button B received in well 256 comes to rest with its bottom side resting against the rear wall of well 256 and its bottom and front edge portions resting against arcuate lug 262 and on button lug 260 of body portion 252. In the case of a 45 ligne button or the largest size button which it is desired to handle, chamber 250 is so constructed that this button is loosely centrally located between lugs 258, 260 and 268 ready for transfer from chamber 250 to pins 148 of transfer 16. A bottom gate 264 and an auxiliary gate 265 coat with the rear wall of well 256 in holding a button therein until it is delivered to transfer 16. Gates 264 and 265 form angular extensions on an elongated on an elongated rod 266 loosely rotatably mounted in lugs 268 of a bracket attached to body portion 252 of chamber 250. A weight 270 fixed to rod 266 tends normally to bias gates 264 and 265 downwardly to inoperative positions away from well 256. A resilient finger 272 mounted on frame F of the machine is engaged by weight 270 as chamber 250 moves from transfer position to button receiving position shown in FIGURE 7, and causes gates 264, 265 to move up to operative positions. As in the case of gate 84, shown in FIGURES 1 and 5, fingers 84 and 272 have sufficient resiliency to allow their respective chambers 14 and 250 to travel part of the distance from the positions shown in FIGURES 1 and 7 towards transfer 16 before weights 94 and 270 are freed and cause gates 84 and 264, 265 to drop away from their operative positions, at which time a button is about to be delivered to transfer 16.

An important feature of chamber 250 is the provision of means which insure that, regardless of the size of button within a predetermined range of sizes, say 20-45 ligne, each size of button selected will be held and disposed in proper centralized relationship for delivery to transfer 16. Referring to FIGURES 7 and 8, chamber 250 is provided with a pair of opposed button gripping and centering fingers 274 and 276. Finger 274 which is pivotally mounted on pin 278 on body portion 252 is provided with an extension 280 having an oversized opening 282 of any suitable shape through which loosely extends a coupling pin 283 which also extends through a circular opening (not shown) in extension 286 forming a part of finger 276 pivoted at 288 on body 252. A spring 290 having its ends attached to brackets on fingers 274, 276 normally maintain the free ends 292, 294 of fingers 274, 276 spaced apart for reception of a button therebetween.

The free end of each finger 274, 276 is provided with two inwardly directed spaced lugs 296 which straddle lugs 258 and 260. The construction just described functions to engage lug 296 with opposite sides of a button when an operating extension 298 on finger 276 is depressed by actuating lever 300. A stop pin carried by body 252 limits the extent of opening of finger 274, 276. The movement of the free ends of fingers 274, 276 towards each other is equal and uniform. Thus whenever operating extension 298 is depressed, a button located between lugs 296 is centralized by fingers 274, 276 in chamber 250 and held therein ready for delivery thereby to transfer 16. Operating lever 300 is fixed to shaft 302 rotatably mounted in bracket 304 secured in a predetermined adjusted position by screw 306 to bracket arm 308 on frame F. An actuating lever 310 is attached to one end of shaft 302. As shown more in detail in FIGURE 9, lever 309 is loosely mounted on shaft 302. It is provided with a slotted opening 312 through which extends a screw 314 threadably

mounted in lever 316 attached to shaft 302. The head 318 of screw 314 is located on the underside of lever 300. A spring 320 encircling screw 314 biases levers 300 and 316 apart, thereby providing means for effecting the desired yielding of lever 300 in closing of fingers 274, 276 depending upon the size of button being handled.

The clockwise movement of chamber 250, as viewed in FIGURE 7, to delivery position relative to transfer 16 is effected by bar 60 and cam 58 in the same manner as described hereinabove in connection with chamber 14, and also as shown and described in Johnson et al., Patent 3,121,411. However, in the form shown in FIGURES 7, 8 and 9, additional mechanism is provided to actuate lever 300. This mechanism comprises a bracket 322 attached by one of the screws 61 which secure cam 102 to bar 60. A cam piece 324 is loosely swingably mounted in bracket 322. As bar 60 moves rearwardly, or upwardly as viewed in FIGURE 7, high portion 325 of cam piece 324 engages actuating lever 310 and causes lever 300 which rests on extension 298 to move downwardly and close fingers 274, 276 whereby a button in well 256 will be held centralized between spaced lugs 296. The design is such that a button is so held for a period of time sufficient to allow chamber 250 to move into delivery position relative to transfer 16 at which time the tip 311 of actuating lever 310 rides off cam piece 324, and fingers 274, 276 are opened by spring 290. On the return movement of bar 60, tip 311 slides over cam portion 325 of cam piece 324 which yields upwardly against the gravity bias thereof, and comes to rest in position to actuate fingers 274, 276 when the button is to be delivered.

Jaws 160, 162 of button chuck 18 shown in FIGURE 3 are provided with button holding elements 161, 163 which are offset rearwardly from the plane of jaws 160, 162, or away from transfer 16, as viewed in FIGURE 3. This construction is provided in order that a button of a selected size, say 24 ligne, will be supported on pins 148 of transfer 16 and located thereon by adapter ring 156 the proper distance above and from the work when it is being attached thereto. In the modified button chuck jaws 160a and 162a shown in FIGURE 4, button holding elements 161a and 163a lie in the plane of jaws 160a and 162a. This is because they are designed to support a larger size button, say 40-45 ligne for attachment to the work which is supported on pins 148 and located by adapter ring 164 for proper transfer thereto. Since this range in size of buttons usually is attached to relatively heavy materials, longer loops of thread are required. This is accomplished by supporting a button a greater distance from the material by jaws, such as 160a and 162a.

As shown in FIGURE 3, adapter ring 156 is provided with an inwardly directed shoulder 155. This shoulder presses against resilient or flexible pins 148 and moves them radially inwardly to predetermined operative positions corresponding with the spacing of holes in buttons of the smaller ranges of sizes, say up to 34 ligne. Shoulder 155 may be of any suitable length. However, it has been found that in adapting the machine to stitching buttons to a man's sack coat, an offset for jaws 160, 162 of one-eighth (1/8) inch gives satisfactory results. Thus the length of shoulder 155 can be one-eighth (1/8) inch long in order to cooperate properly with holding means 161, 163 of jaws 160, 162. This construction makes it possible to adapt the machine as desired without the loss of considerable time in resetting transfer device 16 or attaching buttons to work by the same length of loops of thread, which would be entirely unsatisfactory.

In the case of adapter ring 164, shown in FIGURE 4, the ring has no effect upon the position of pins 148 and their outward radial movement is constrained by the inner surface of head 153. Ring 164, however, is narrower than ring 156 and performs the function described hereinabove. It also serves as a seat for buttons to be transferred into holding means 161a and 163a of jaws 160a, 162a.

What we claim is:

1. In a button stitching machine including a button rack for holding a stack of buttons, a guard member, means mounting said member adjacent said rack to prevent the removal of more than one button at a time from said stack, a button ejector, and means for operating said ejector to effect the delivery of a single button from said rack; the combination with said button holding rack of a button adapter wherein said button holding rack can accommodate a range of size of buttons, and said button adapter can hold a range of size of buttons different from that which can be held by said rack alone, and means for mounting said adapter within said rack, whereby said different range of button sizes can be fed by said ejector from said rack.

10 2. The invention defined in claim 1 wherein said adapter can support a plurality of ranges of button sizes, and said mounting means for said adapter comprise means for securing said adapter in selected operative positions within said rack determinative by the range of button sizes to be stored in said rack and fed therefrom, with said securing means disposed within said rack.

20 3. The invention defined in claim 2 wherein said rack comprises an elongated generally U-shaped trough having a flat central elongated portion located between the walls of said U, and said adapter is an elongated generally U-shaped trough corresponding generally in cross-section to said rack, mounting means formed in said flat portion of said rack, and wherein said mounting means for said adapter comprise means carried on the underside of said adapter coacting with said mounting means in said flat portion of said rack to secure said adapter in a plurality of operative positions in said rack with the walls of said adapter substantially parallel to the walls of said rack.

25 4. In a button stitching machine including a button rack for holding a stack of buttons, a guard member, means mounting said member adjacent said rack to prevent the removal of more than one button at a time from said stack, a button ejector, and means for operating said ejector to effect the delivery of a single button from said rack, and including a button chute, means for delivering a button ejected from said rack into said chute, a plurality of selectively usable button delivery chambers for holding a button delivered thereto by said chute, a mount for a selected button delivery chamber, means for securing said selected button chamber suitable for holding a selected size of button to said mount, and means for delivering a button from said chute into said selected chamber;

30 55 the combination with said chamber of a button transfer device, means detachably mounted on said device for adapting said device to receive a selected size of button from said selected chamber, a button chuck for holding said selected size of button, means for connecting said chamber to a drive means for moving said chamber to deliver a button therefrom to said transfer device, means for connecting said transfer device to a drive means for moving said transfer device with a button carried thereby for delivery to said button chuck.

60 65 5. The invention defined in claim 4 wherein said means for adapting said button transfer device includes a plurality of selectively usable rings for adapting said transfer device to support and carry buttons of different sizes, and means detachably mounting a selected ring on said transfer device for effecting the transfer of buttons of a selected size.

70 75 6. The invention defined in claim 5 wherein transfer device includes a plurality of resilient button supporting pins, and each selected ring coats with said pins to position said pins to enter the holes of a selected size of button and support said button thereon for delivery to said

button chuck, said chuck comprising spaced opposed jaws positioned to support buttons of said selected size a predetermined distance above and from the material to which said button is to be attached.

7. The invention defined in claim 6 wherein said button chuck comprises a body portion and a pair of opposed button holding jaws, and means detachably mounting said jaws in said body portion for use or replacement by a pair of jaws capable of holding buttons of a different selected size.

8. In a button stitching machine including a button rack for holding a stack of buttons, a guard member, means mounting said member adjacent said rack to prevent the removal of more than one button at a time from said stack, a button ejector, and means for operating said ejector to effect the delivery of a single button from said rack, and including

a button chute, means for delivering a button ejected from said rack into said chute, a plurality of selectively usable button delivery chambers for holding a button delivered thereto by said chute, a mount for a selected button delivery chamber, means for securing said selected button chamber suitable for holding a selected size of button to said mount, and means for delivering a button from said chute into said selected chamber, and including

a button transfer device, means detachably mounted on said device for adapting said device to receive a selected size of button from said selected chamber, a button chuck for holding said selected size of button, means for moving said chamber to deliver a button therefrom to said transfer device, means for moving said transfer device with a button carried thereby to a point of transfer relative to said button chuck, and means for effecting the delivery of said button from said transfer device into said button chuck and wherein

said button transfer device includes a plurality of selectively usable rings for adapting said transfer device to support and carry buttons of different sizes, and means detachably mounting a selected ring on said transfer device for effecting the transfer of buttons of a selected size, and said transfer device also includes a plurality of resilient button supporting pins, and each selected ring coacts with said pins to position said pins to enter the holes of a selected size of button and support said button thereon for delivery to said button chuck, said chuck comprising spaced opposed jaws positioned to support buttons of said selected size a predetermined distance above and from the material to which said button is to be attached;

the combination with said button transfer device of said chuck wherein said button chuck comprises a body portion and a set of opposed button holding jaws, fastening means detachably mounting said set of jaws in said body portion for use with one selected size of button or replacement by another set of jaws capable of holding a different selected size of button, and wherein a plurality of sets of jaws includes button holding means coplanar with the body of said jaws for certain selected sizes of buttons, and other sets of jaws provided with button holding means offset from the plane of the bodies of said jaws for holding a range of smaller sizes of buttons held therein closer to the material to which it is to be attached.

9. In a button stitching machine including a button chuck and a table mounting said chuck movable in a plurality of paths in a single plane for positioning a button and the material to which it is to be attached in a plurality of stitching positions in accordance with a predetermined stitching pattern, said chuck comprising a body portion, a plurality of sets

of selectively usable opposed button holding jaws, means for detachably securing a selected set of jaws on said body whereby buttons of a selected size can be held for attachment to said material, and means for moving said jaws away from each other to position a button there-between and to release a stitched button therefrom;

the combination of said sets of jaws with said means for detachably securing a selected set of jaws on said body wherein said sets of jaws include jaw members, each having a planar body portion and opposed button holding elements substantially coplanar with said body portions, said sets of jaws also including jaw members having body portions with button holding elements longitudinally offset from said last-named body portions.

10. The invention defined in claim 9 including a button transfer device coacting with said button chuck to transfer buttons into said jaws of said chuck, said transfer device comprising a movable body portion, a button supporting head having a plurality of button supporting pins, a selectively usable adapting ring, means mounting said ring on said head for positioning said pins for entry into the holes of one range in size of buttons for use in delivering buttons to said sets of jaws wherein said button holding elements are substantially coplanar with the body portions thereof, and another adapting ring for mounting on said head for moving said pins closer together for entry into the holes in buttons in a range of size smaller than said first-named range of size buttons when said transfer device is to transfer buttons to said offset button holding elements.

11. The invention defined in claim 10 including a plurality of button holding and delivering chambers, means for delivering buttons of a selected size in succession from a source of supply to a selected chamber capable of holding said selected size of button, and means for moving said chamber relative to said transfer device to effect the delivery of a button from said chamber to said transfer device.

12. A button transfer device comprising a head, a plurality of resilient button supporting pins mounted in said head and extending outwardly therefrom, said head having a portion encircling a portion of said pins to limit their outward flexing to positions corresponding with the spacing of holes in a range of buttons of the largest sizes to be handled by said device, and an adapter ring adapted to be mounted on said means for effecting the radial inward movement of said pins to operative positions corresponding to the spacing of holes in a range of buttons of smaller sizes.

13. The invention defined in claim 12 wherein said adapter ring has a shoulder portion engaging said pins to force them radially inwardly, and said adapter ring has means for securing said ring in operative position.

14. A button receiving and delivering chamber comprising a body portion, a button well formed in said body portion, means for delivering a button of any selected size to said well, opposed centralizing fingers in said well, actuating means for moving said fingers into engagement with opposite sides of said button to center and hold said button in centered position in said well, means coacting with said fingers to support said button in said well, and said actuating means having means for releasing said fingers from said button when said button is delivered from said well of said chamber.

15. The invention defined in claim 14 including a button transfer device having a rotatable head and a plurality of flexible button supporting pins projecting therefrom, selective means for adapting said transfer device to handle a wide range of sizes of buttons comprising adapting rings mountable on said head for conforming the spacing of said pins to the hole spacing of a selected size of button, and means for moving said chamber towards

said transfer device to effect the delivery of said button onto said pins of said transfer device.
